CASE FOR AN IGNITION TIMING LIGHT

Joseph P. Pennimpede, Danvers, Henry B. Hoover, Lincoln, and Renato Di Filippo, Wenham, Mass., assignors to Edgerton, Germeshausen & Grier, Inc., Bedford, Mass., a corporation of Massachusetts

Filed June 9, 1964, Ser. No. 80,336

Term of patent 14 years

(Cl. D52—1)

FIG. 1

FIG. 2

FIG. 3

FIG. 4

FIG. 5

FIG. 6

FIG. 7

FIGURE 1 is an isometric view of a case for an ignition timing light showing our new design;

FIGURE 2 is a side elevational view thereof;

FIGURE 3 is an elevational view of the other side thereof;

FIGURE 4 is a top plan view thereof;

FIGURE 5 is a bottom plan view thereof; and

FIGURES 6 and 7 are front and rear elevational views respectively thereof.

We claim:

The ornamental design for a case for an ignition timing light, substantially as shown.
